CLAIM

(21) Appl. No.: **29/373,760**

The ornamental design for a decorative framed rattan panel trash bin, as shown and described.

(22) Filed: **May 20, 2011**

DESCRIPTION

(51) **LOC (9) Cl.** **09-09**

FIG. 1 is a side view of the decorative framed rattan panel trash bin of the present invention with the side door in the open position.

(52) **U.S. Cl.** **D34/7; D34/6**

FIG. 2 is a front view of the decorative framed rattan panel trash bin of the present invention with the front doors in the open position.

(58) **Field of Classification Search** D34/1,
D34/5, 6, 7, 8, 9, 10, 11; 220/908-913; D6/396,
D6/432, 440, 509, 510, 511

FIG. 3 is a front view of the decorative framed rattan panel trash bin of the present invention with the front and side doors in the closed position.

See application file for complete search history.

FIG. 4 is a side perspective view of the decorative framed rattan panel trash bin of the present invention with the front and side doors in the closed position.

(56) **References Cited**

FIG. 5 is a side view of the decorative framed rattan panel trash bin of the present invention with the side door in the closed position.

U.S. PATENT DOCUMENTS

FIG. 6 is a back view of the decorative framed rattan panel trash bin of the present invention with the side door in the closed position; and,
